FLARING AND BURNISHING TOOL WITH LOST MOTION CONNECTION

George E. Franck, Riverside, Ill., assignor to The Imperial Brass Manufacturing Company, a corporation of Illinois

Application August 10, 1956, Serial No. 603,425

9 Claims. (Cl. 153—79)

This invention relates to a tube flaring tool and in particular to a tube flaring tool adapted automatically to burnish the flared end of the tube.

When tubing, such as copper tubing, is flared at an end to arrange the tubing for connection to a fitting, it is necessary that the inner surface of the flared portion be relatively true and regular. As common flaring tools incorporate a rotatable flaring cone which is either faceted or carries rollers to reduce the frictional drag, irregularities may result in the flare surface requiring a subsequent burnishing operation in which the surface is burnished or lapped to a true frusto-conical configuration.

It is the principal object of this invention to provide a new and improved tube flaring tool with integral means for effecting proper burnishing of the flared tube.

Another object is to provide such a tube flaring tool wherein the burnishing operation is effected by yieldable means maintaining the flaring cone in facial engagement with the flare surface for a desirable amount of angular rotation of the cone prior to the separation of the cone from the flare surface.

A further object is to provide a simply constructed, economically manufactured tube flaring tool wherein the burnishing operation is completely automatic requiring no manipulation of any part of the tool by the operator thereof save reverse rotation of the handle.

Still another object of the invention is to provide such a tube flaring tool capable of ready adjustment of the amount of burnishing that is automatically obtained.

Other features and advantages will be apparent from the following description taken in connection with the accompanying drawings wherein:

Figure 1 is an elevational view of a tube flaring tool embodying the invention, with the end of a tube to be flared secured therein;

Figure 2 is an enlarged, fragmentary sectional view taken approximately along the line 2—2 of Figure 1;

Figure 3 is an enlarged, fragmentary sectional view taken approximately along the line 3—3 of Figure 1, but with the elements disposed as at the end of the flaring operation;

Figure 4 is a sectional view similar to that of Figure 3, but with the tool elements disposed as during the burnishing operation;

Figure 5 is an elevational view of a modified form of tube flaring tool having means for adjusting the amount of burnishing;

Figure 6 is an enlarged sectional view taken approximately along the line 6—6 of Figure 5;

Figure 7 is an enlarged end view of the flaring cone.

In the exemplary embodiment of the invention as disclosed in Figures 1 to 4 and 7 of the drawings a tube flaring tool generally designated 10 is shown to comprise a frame member 11 arranged to carry a sleeve 12 for threaded advancement and withdrawal relative to a tube end 20 held in a clamping means 13 carried by one portion of the frame member. Extending completely through the sleeve 12 is a rod-like carrier member 14

2

provided with a flaring cone 15 at the end thereof adjacent clamping means 13. At the opposite or outer end of carrier 14 is provided an operating handle 16. Means for preventing relative rotational movement between handle 16 and sleeve 12, while allowing relative longitudinal movement therebetween, comprise a pin 17 secured to one of these elements and a complementary, longitudinally extending recess 18 in the other thereof. Yieldable means such as helical spring 19 are arranged 10 to extend between sleeve 12 and carrier 14 so as to urge cone 15 away from the sleeve and toward tube clamping means 13. When sleeve 12 is in the withdrawn position 15 wherein cone 15 is spaced substantially away from the tube clamping means, the cone is spaced a predetermined distance from the end of the sleeve. When the cone is pressed against the tube end 20, the spring is overcome until the sleeve end abuts the cone and positively forces it against tube end to effect the flare, as best seen in Figure 3. However, as seen in Figure 4, 20 upon the initial withdrawal of sleeve 12 subsequent to the flaring operation, spring 19 maintains cone 15 in engagement with the flared tube end automatically effecting a burnishing operation.

Frame member 11 comprises a rigid, yoke shaped 25 structure having a bifurcated, inturned support portion 11a at its open end, and a threaded bore 11b extending through the opposite closed end. Tube clamping means 13 may be of any conventional type and is illustratively shown as of the split block type adapted to be carried 30 on support portion 11a. Tube end 20 is inserted through means 13 so as to extend a predetermined distance above a frusto-conical flaring surface 13a provided thereon depending on whether the flare is to be made against the surface 13a or in the air.

Sleeve 12 is exteriorly threaded for engagement with 35 threaded bore 11b and is provided at its outer end with a radial enlargement or collar 12a. While pin 17 may be fixedly secured to either of handle 16 or sleeve 12, for illustrative purposes I have shown the pin as fixedly 40 secured to the handle and recess 18 as being provided in collar 12a of the sleeve. A bore extends completely through sleeve 12 having an outer portion 12b and an enlarged diameter inner portion 12c with a radial shoulder 12d resultingly formed therebetween. At its outer end, 45 bore portion 12b is radially enlarged to form a radial surface or shoulder 12e. At its inner end, bore portion 12c opens into a radial surface 12f defining the inner end of the sleeve.

Carrier 14 comprises a rod having a cylindrical midportion 14a, and an outer portion 14b having a non-circular cross section with the sides thereof being smaller than the diameter of mid portion 14a thereby forming a shoulder 14c between the middle and outer portions. Handle 16 is provided with a hub 16a having a bore 16b there- 50 through complementary to outer portion 14b of the carrier and adapted to prevent rotative movement between the handle and the carrier. In the embodiment of the drawings the cross section of portion 14b and bore 16b is square. Means such as screw 16c are provided for 55 fixedly securing the handle to the carrier against shoulder 14c. Pin 17 projects from handle 16 into recess 18 with a sliding fit, allowing longitudinal movement of the handle relative to the sleeve while preventing rotational movement therebetween. As may best be seen in Fig. 3 the 60 longitudinal inward movement of the carrier relative to sleeve 12 is limited by the abutment of handle hub 16a with sleeve shoulder 12e.

Cone 15 is mounted on the inner end of carrier 14 and 65 is annularly stepped to form a first shoulder 15a and a second shoulder 15b. As shown, cone 15 may be faceted and chrome plated to provide improved, low friction working of the tube end. Helical spring 19 is re-

ceived around the mid portion 14a of the carrier in sleeve bore portion 12c to extend between sleeve shoulder 12d and cone shoulder 15a under suitable compression. It is preferable that spring 19 be of sufficient strength to force the cone against the tube end to effect a satisfactory burnishing operation. Sleeve shoulder 12f is adapted to abut cone shoulder 15b when the sleeve is moved longitudinally inwardly while the cone is resisted axially such as by tube end 20 during the flaring operation.

In the operation of flaring tool 10 with tube end 20 secured in clamping means 13 as seen in Figure 1, handle 16 is suitably rotated (herein referred to as forward) to advance sleeve 12 toward clamping means 13. This rotation is effected through pin 17. Carrier 14 is concurrently rotated by the handle, thereby effecting rotation of flaring cone 15 carried on the other end thereof. As seen in Figure 1, carrier 14 is urged by spring 19 so that the inner end of the handle hub 16a abuts sleeve shoulder 12e and cone shoulder 15b is spaced substantially from sleeve shoulder 12f. Upon engagement of cone 15 with tube end 20, resistance to the forward movement of carrier 14 results tending to overcome spring 19 and move sleeve shoulder 12f relatively toward cone shoulder 15b until the shoulders abut. Thereafter advancement of cone 15 is continued until tube end 20 is forced into facial contact with flaring surface 13a to complete the flaring operation, as seen in Figure 3.

Reverse rotation of handle 16 now causes sleeve 12 to be threadedly withdrawn through bore 11b while cone 15 is being rotated. However, the action of spring 19 causes cone 15 to maintain forceful engagement with the flared surface of tube end 20. Thus, the cone is positionally longitudinally fixed while rotating, thereby effecting a burnishing action against the flared surface of tube end 20. This burnishing action continues until, under the urging action of spring 19, handle hub 16a is caused to abut sleeve shoulder 12e thereby preventing further movement of sleeve shoulder 12f away from the cone shoulder 15b. Continued reverse rotation of handle 16 effects withdrawal of carrier 14 and cone 15 thereon together with sleeve 12, allowing the tool to be returned to the starting position of Figure 1.

In the modified tool 110 of Figures 5 and 6, a modified sleeve 112, carrier 114, and cone 115 are provided wherein the sleeve is provided with squared bore portion 112g in which is received a complementary squared outer portion 114b of the carrier. Carrier portion 114b extends into a squared bore 116b in the handle so as to provide a non-rotative connection between handle 116 and sleeve 112.

In this form, a screw 116c extends through handle 116 and is secured adjustably to the outer end of carrier portion 114b. Thus, as best seen in Figure 5, carrier 114 may be positioned axially relative to sleeve 112 so that the space between sleeve shoulder outer end 112f and cone shoulder 115b may be predetermined and fixed as desired. As the spacing between shoulders 112f and 115b determines the amount of withdrawal of sleeve 112 allowed before cone 115 is withdrawn from engagement with the flared tube surface, the amount of burnishing effected is thus made controllable through the adjustment of screw 116c. In all other respects, the operation of tool 110 is similar to operation of tool 10.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A tube flaring and burnishing tool comprising a frame member having a threaded bore through one portion thereof and a support portion adapted to have a tube end supported therein in alignment with said bore, an externally threaded sleeve engaged in said bore for

5 rotative movement relative to said frame member and for axial movement as an incident to such rotative movement, an abutment means carried by said sleeve, tube flaring means including a carrying member mounted in said sleeve for movement axially thereof and a flaring cone fixed on that end of said carrying member adjacent the support portion of said frame, means including a handle for simultaneously rotating said sleeve and said flaring means in either direction to advance or retract said sleeve, stop means associated with said sleeve and with said flaring means restricting to a desired amount the relative axial movement between said sleeve and said flaring means, said stop means including the end of said sleeve adjacent said cone and means on said flaring means adapted to be engaged by said sleeve end, after a predetermined advance of said sleeve by rotation in an advancing direction, for effecting positive axial movement of said flaring cone to effect a flaring operation upon continued rotation of said sleeve in an advancing direction, and compression spring means interposed between said abutment means and said flaring means forcefully maintaining said cone urged against a tube that has been flared to effect a burnishing thereof during retracting rotation of said sleeve until said flaring means has traveled the limit of its axial movement relative to said sleeve.

2. A tube flaring and burnishing tool comprising a frame member having a threaded bore through one portion thereof and a support portion adapted to have a tube end supported therein in alignment with said bore, an externally threaded sleeve engaged in said bore for rotative movement relative to said frame member and for axial movement as an incident to such rotative movement, an abutment means carried by said sleeve, tube flaring means including a carrying member mounted in said sleeve for movement axially thereof and a flaring cone fixed on that end of said carrying member adjacent the support portion of said frame, means coupling said carrying member and said sleeve for joint rotation while permitting relative axial movement, compression spring means interposed between said abutment means and said flaring means positively and forcefully urging said cone in the direction of the support portion of said frame member, means associated with said sleeve and with said flaring means limiting relative axial movement of said flaring means under the influence of said spring to a fraction of the movement of said sleeve, the end of said sleeve adjacent said flaring cone serving as an abutment engaging said flaring means positively to limit axial movement of said flaring means relative to said sleeve in a direction in opposition to the action of said spring, and a handle for simultaneously rotating said coupled sleeve and flaring means to flare a tube end after engagement of a tube end by said cone and abutment of said sleeve end with said flaring means during rotation of said sleeve in a direction to advance the same and to burnish the flared tube end by forcefully maintenance of said cone against the flared tube end during initial rotation of said sleeve in a direction to retract the same.

3. A tube flaring and burnishing tool comprising a frame member having a threaded bore through one portion thereof and a support portion adapted to have a tube end supported therein in alignment with said bore, an externally threaded sleeve engaged in said bore for rotative movement relative to said frame member and for axial movement as an incident to such rotative movement, an abutment means carried by said sleeve, tube flaring means including a carrying member mounted in said sleeve for movement axially thereof and a flaring cone fixed on that end of said carrying member adjacent the support portion of said frame, a compression spring compressed between said abutment means and said flaring means for forcefully urging said cone axially away from said sleeve, means carried by the other end of said carrying member limiting the axial movement of

said carrying member relative to said sleeve as effected by said spring whereby said cone is normally disposed spaced axially from the adjacent end of said sleeve, said adjacent sleeve end being disposed to abut said cone and limit axial movement of said carrying member relative to said sleeve in the opposite direction, and means for simultaneously rotating both said sleeve and said flaring means to move both said sleeve and said flaring means axially until said cone makes contact with a tube held in said support portion then to move only said sleeve axially until the end thereof abuts said cone and then to resume axial movement of both said sleeve and said flaring means to effect a flaring operation, reverse rotation of said sleeve and of said flaring means upon completion of said flaring operation moving only said sleeve axially until said means carried by the other end of said carrier comes into play to limit relative axial movement between said sleeve and said flaring means, said spring during such relative axial movement maintaining said cone in engagement with the flared tube end and having sufficient strength to cause said cone to burnish the flared end of the tube. 20

4. A tube flaring and burnishing tool, comprising: a frame member having a threaded bore through one portion thereof and a support portion adapted to have a tube end supported therein in alignment with said bore; an externally threaded sleeve engaged in said bore for axial and rotative movement; a carrier in said sleeve axially slideable therein and having ends projecting outwardly from the opposite ends of said sleeve; a flaring cone fixed on one end of said carrier adjacent said support portion; a compression spring compressed between said sleeve and said cone for forcefully urging said cone axially away from said sleeve; means carried by the other end of said carrier for limiting the axial movement of said carrier relative to said sleeve as effected by said spring whereby said cone is normally disposed spaced axially from the adjacent end of said sleeve, said adjacent sleeve end being disposed to abut said cone and limit axial movement of said carrier relative to said sleeve 40 in the opposite direction, and means for simultaneously rotating both said sleeve and said flaring cone carrier to move both said sleeve and said carrier axially until said cone makes contact with a tube held in said support portion, then to move only said sleeve axially until the end thereof abuts said cone and then to resume axial movement of both said sleeve and said carrier to effect a flaring operation, reverse rotation of said sleeve and said carrier, upon completion of said flaring operation, 45

5 moving only said sleeve axially until said means carried by the other end of said carrier comes into play to limit relative axial movement between said sleeve and said carrier, said spring during such relative axial movement maintaining said cone in engagement with the flared tube end and having sufficient strength to cause said cone to burnish the flared end of the tube.

5. The tool of claim 4 wherein said sleeve has a stepped bore extending axially therethrough with a radial shoulder formed between portions of different diameter and said spring is received in an enlarged portion of the bore between said shoulder and said flaring cone.

10 6. The tool of claim 4 wherein the means carried by the other end of said carrier for limiting the relative axial movement thereof and said means for simultaneously rotating both said sleeve and said carrier comprise a handle member nonrotatably secured to said other end of the carrier and a cooperating pin and recess, one of said pin and recess being carried by said handle and the other by said sleeve, said pin being at all times engaged in said recess to couple said sleeve and said carrier for joint rotational movement while permitting relative axial movement of said sleeve and said carrier.

15 7. The tool of claim 4 wherein the means for limiting relative axial movement between said carrier and said sleeve is adjustable to vary the amount of burnishing action.

20 8. The tool of claim 4 wherein said other end of the carrier has a noncircular transverse cross section, a handle is connected to said other end, said handle being provided with a complementary noncircular recess for nonrotative but axially displaceable reception of said other end therein.

25 9. The tool of claim 4 wherein said spring surrounds said carrier near its cone carrying end, and said sleeve is provided with an axial recess opening toward said support portion in which said spring is received.
